UNITED STATES PATENT OFFICE.

LILLIAN GROTHAUS, OF NEW BREMEN, OHIO.

COMBINATION TABLE AND IRONING BOARD.

Application filed September 13, 1924. Serial No. 737,544.

This invention relates to a combination table and ironing board and it is an object of the invention to provide a novel and improved device of this general character whereby the ironing board, when not in use, is concealed beneath the top of the table.

It is also an object of the invention to provide a novel and improved device of this general character wherein the table top, when the ironing board is extended for use, may serve as a medium to prevent tilting of the board.

An additional object of the invention is to provide a novel and improved device of this general character comprising a table with a removable top together with a foldable board adapted to be housed within the supporting structure for the table top and wherein means are provided to effectively brace or strengthen the sections of the board when extended for use.

Furthermore, it is an object of the invention to provide a device of this general character wherein novel and improved means are employed for effectively maintaining the removable table top in applied position.

The invention consists in the details of construction and in the combination and arrangement of the several parts of my improved combination table and ironing board whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view partly in section and partly in elevation illustrating a combined table and ironing board constructed in accordance with an embodiment of my invention, the ironing board being shown compacted and housed within the table frame;

Figure 2 is a sectional view taken substantially on the line 2—2 of Figure 1, looking in the direction of the arrow;

Figure 3 is a fragmentary view partly in section and partly in elevation showing the

ironing board extended for use and with the table top in hanging position;

Figure 4 is a fragmentary view in perspective of an end member of the frame illustrating the keeper for the bolt;

Figure 5 is a view in bottom plan of the table top as herein disclosed;

Figure 6 is a view in bottom plan of the ironing board extended and certain of the parts directly associated therewith;

Figure 7 is a fragmentary sectional view taken substantially on the line 7—7 of Figure 1;

Figure 8 is a fragmentary sectional view taken substantially on the line 8—8 of Figure 3.

As disclosed in the accompanying drawings, the table comprises a frame F consisting of the side members 1 and the end members 2, the upper edges of which being coplanar or flush and the lower marginal portions of the side members 1 adjacent one of the end members 2 are connected by the interposed reinforcing or bracing member 3.

Coacting with each end of the frame F are the supporting legs 4 the upper end portions of which having direct contact with the adjacent ends of the side members 1 of the frame, said upper end portions being connected by the transversely disposed member 5. The adjacent end member 2 of the frame F is directly connected, as herein disclosed, to said upper portions of the legs 4 by the screws 6 whereby the frame F and the supporting legs 4 are maintained in desired assembled relation. It is to be noted that in the assembly of the frame F and the supporting legs 4, each of the transversely disposed members 5 is slightly spaced from the adjacent end member 2.

The table top T is of requisite dimensions and at a desired point inwardly of one end of said top T is secured the depending blocks 7 which are adapted to abut or have close contact from within with one of the end members 2 while the opposite end portion of the table has secured thereto the underhung clips or lugs 8 which are adapted to be received within suitable recesses or pockets 9 provided in the inner face of the second end member 2 whereby the table top T will be effectively maintained in applied position. The under surface of the table

top T at a point substantially midway of the blocks 7 but outwardly thereof is provided with a sliding bolt 10 which is adapted to engage within a keeper 11 carried by 5 the outer face of the adjacent member 5. By this means, the top T may be readily and conveniently locked in its applied or working position.

The underhung lugs 8 constitute the extremities of the straps 12 but are suitably offset with respect thereto, said straps 12 being directly secured by the screws 14 or the like to the under surface of the top T.

These straps 12 are disposed lengthwise 15 of the top T and the inner extremities thereof are continued by the perpendicularly related extensions or arms 15, the extremities of which carrying the lips or flanges 16 disposed in a direction away from the lugs 8 20 and substantially at right angles to the extensions or arms 15. These arms 15 are of a length to substantially bridge the member 5 provided with the keeper 11 and the adjacent end member 2 so that the flanges or lips 25 16 will engage the inner face of said end member 2 when the top T is supported in a hanging position at such end of the frame F. This positioning or adjustment of the top T may be readily effected, after the bolt 10 30 has been moved into release position, by slightly lifting the end portion of the top provided with the blocks 7 and then sliding said top T along the frame F.

The opposed faces of the side members 1 35 of the frame F at a predetermined point inwardly of the end thereof with which the bolt 10 is adapted to cooperate, are provided with the brackets or clips 17. These brackets 17 are in transverse alignment and secured to the lower marginal portions of the members 1.

Arranged between the side members 1 is a cross plate 18 the opposite end portions of 40 which adjacent its lower margin being provided with the outstanding trunnions 19 which are pivotally connected with the brackets 17 whereby said plate is supported for swinging movement in a direction lengthwise of the frame F.

50 This plate 18 is of such width as to have its free or outer longitudinal marginal portion terminate slightly inwardly of the upper edges of the side members 1 when said plate 18 is in its raised position and hinged 55 edly connected to the central portion of the free longitudinal marginal portion of this plate 18 is a cleat 20. This cleat 20 is of a length to have its opposite end portions terminate inwardly of the straps 12 and the arms or extensions 15 carried thereby.

The ironing board B comprises the two sections 21 and 22 having the adjacent end portions thereof pivotally connected by the concealed hinges 23 whereby the section 22 65 may be readily folded or superimposed upon

the section 21. The sections 21 and 22 are substantially the same length but of a length less than the distance between the end members 2 of the frame F so that said board B when folded may be readily housed or confined within said frame. 70

The section 21 has secured to the under surface thereof the parallel guide cleats 24 having their outer end portions directly connected from above with the extremities 75 of the cleat 20. The opposite end portions of the cleats 24 extend a slight distance beyond the outer end of the section 21 and are connected from below by the cross member 25. This cross member 25 has extending 80 therealong the flanges 26 spaced apart a distance to snugly receive therebetween the upper marginal portion of an end member 2 of the frame F when the section 21 is raised 85 into working position.

Positioned between and slidably supported by the guide cleats 24 is a slide 27 which, when extended, serves as a support for the section 22 of the board when swung outwardly. 90

It is to be particularly noted that the sections 21 and 22 are of a width less than the distance between the straps 12 and the extensions or arms 15 carried thereby so that the board when folded or compacted within 95 the frame F will offer no hindrance or obstruction to the requisite sliding movement of the table top T. When so folded it will also be noted that the cross plate 18 is lowered and also out of the path of 100 travel of said arms 15.

By permitting the top T to hang at an end of the table, it will be readily noted that said top provides means effectively operating to prevent tilting of the board B when 105 in use. Furthermore, this hanging of the top maintains the same in a position to conveniently permit its return to working position when desired.

From the foregoing description it is 110 thought to be obvious that a combination table and ironing board constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed. 115

I claim:—

1. A device of the class described comprising, in combination, a table frame, a removable top therefor, a plate positioned between and disposed transversely of the side 120 125 130

members of the frame, means for pivotally connecting said plate with said side members, an ironing board section hingedly connected with said plate, a second ironing board section hingedly connected with the first named ironing board section and adapted to be superimposed thereon, means for supporting said second section extended in substantial alignment with the first named section, and means carried by the first named section to engage an end member of the frame when the ironing board is in position for use.

2. A device of the class described comprising, in combination, a table frame, an ironing board adapted to be housed within said frame, a table top adapted to be mounted upon the frame, depending blocks carried by the top and adapted to abut an end member of the frame, and lugs depending from

said top, the second end member of the frame being provided with recesses to receive said lugs.

3. A device of the class described comprising, in combination, a table frame, an ironing board adapted to be housed within said frame, a table top adapted to be mounted upon the frame, depending blocks carried by the top and adapted to abut an end member of the frame, lugs depending from said top, the second end member of the frame being provided with recesses to receive said lugs, and coacting means carried by the end portion of the table top provided with the blocks and the adjacent end of the frame for locking the top in applied position.

In testimony whereof I hereunto affix my signature.

LILLIAN GROTHAUS.
